Primary Examiner — Omeed Agilee(74) *Attorney, Agent, or Firm* — Gloria Tsui-Yip; Gottlieb, Rackman & Reisman, P.C.(57) **CLAIM**

The ornamental design for a fluid container, as shown and described.

DESCRIPTION

FIG. 1 is a front elevational view of a fluid container showing our new design;

FIG. 2 is a left side elevational view thereof;

FIG. 3 is a rear elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines in the drawings depict portions of the fluid container that form no part of the claimed design.

1 Claim, 4 Drawing Sheets(56)
